UNITED STATES PATENT OFFICE

159,654

CAST METAL APPLIQUÉ FILIGREE

William H. Leavin, New York, N. Y.

Application December 31, 1948, Serial No. 150,486

Term of patent 3½ years

(Cl. D54—2)

To all whom it may concern:

Be it known that I, William H. Leavin, a citizen of the United States and residing in the city, county, and State of New York, have invented a new, original, and ornamental Design for a Cast Metal Appliqué Filigree, of which the following is a specification, reference being had to the accompanying drawing, forming part hereof and in which the single figure is a plan view of cast metal appliqué filigree showing my new design.

I claim:

The ornamental design for a cast metal appliqué filigree, substantially as shown.

WILLIAM H. LEAVIN.
